US0D1051869S

(12) **United States Design Patent** (10) **Patent No.:** **US D1,051,869 S**
(45) **Date of Patent:** **** Nov. 19, 2024**

(54) **INTERACTIVE SMARTBOARD**

(71) Applicants: **GUANGZHOU SHIYUAN ELECTRONICS CO., LTD.**
Guangdong (CN); **GUANGZHOU SHIZHEN INFORMATION TECHNOLOGY CO., LTD.**
Guangdong (CN)

(72) Inventor: **Jiaying Kuang**, Guangdong (CN)

(**) Term: **15 Years**

(21) Appl. No.: **29/730,998**

(22) Filed: **Apr. 10, 2020**

(30) **Foreign Application Priority Data**

Oct. 11, 2019 (CN) 201930553628.8

(57) **CLAIM**

The ornamental design for an interactive smartboard as shown and described.

DESCRIPTION

FIG. 1 is a front view of an interactive smartboard showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is an enlarged detail view of portion 8 encircled in FIG. 4;

FIG. 9 is an enlarged detail view of portion 9 encircled in FIG. 2;

FIG. 10 is an enlarged detail view of portion 10 encircled in FIG. 2; and,

FIG. 11 is an enlarged detail view of portion 11 encircled in FIG. 6.

Dash-dash broken lines illustrate portions of the interactive smartboard that form no part of the claimed design. Dot-dash broken lines encircling portions of the interactive tablet reference the enlarged detail views and form no part of the claimed design.

1 Claim, 11 Drawing Sheets
